[57] ABSTRACT

The invention relates to a device for producing a false selvedge on a fabric, comprising two rods together receiving slidingly a first and a second block, each supporting thread guides, said rods being provided at their ends with abutments for the blocks, while a spring is located between the blocks to tend constantly to separate one from the other, means moreover being provided to displace the thread guides laterally when the blocks move with respect to one another, and in this device the thread guides of the second block are mounted pivotally on this other block, the thread guides, mounted pivotally on the second block being controlled in their pivotal movement by a linking member mounted pivotally on the first block receiving the thread guide in oscillating position.

**DEVICE FOR PRODUCING A FALSE SELVEDGE
ON A FABRIC AS WELL AS WEAVING LOOMS
PROVIDED WITH SUCH A DEVICE**

The invention relates to a device for producing a false selvedge on a fabric as well as looms provided with such a device.

Devices of this kind are already known consisting of thread guides mounted pivotally on supports, these supports moreover being able to move toward one another, so that, by means of the simultaneous movements of the thread guides and the supports, one obtains an interlacing of the threads passing through these thread guides with the weft threads of the fabric produced. These fastening threads, together if necessary with a knotting thread, then constitute a false selvedge located on the edge of a fabric.

All these known devices are of complicated construction and therefore costly and in addition their reliability is uncertain, bearing in mind the great accuracy required on account of the small size of the parts, the very small movements these moving parts must execute and the rapidity with which this must be effected. In addition, only nylon threads can be used for fastening, as the path followed by the threads is very tortuous.

Thus, in these known devices, it frequently happens that the thread guides through which the fastening threads pass, begin to vibrate and possibly enter into resonance, so that correct functioning becomes uncertain, these vibrations even being able to damage the device irretrievably when the thread guides meet head-on.

These vibrations are also very detrimental to the good interlacing of the fastening threads in the production of a false selvedge.

The particular object of the present invention is to overcome these disadvantages and relates to this end to a device for producing a false selvedge on a fabric, comprising two rods together receiving slidably a first and second block, each supporting thread guides, said rods being provided at their ends with abutments for the blocks, while a spring is located between the blocks to tend constantly to separate one from the other, means being provided to displace the thread guides laterally when the blocks move with respect to one another, which device is characterised in that the thread guides of the first block are mounted so that they can oscillate, while the thread guides of the second block are mounted pivotally on this other block, the thread guides, mounted pivotally on the second block being controlled in their pivoting movement by a linking member mounted pivotally on the first block receiving the thread guide in oscillating position.

The device according to the invention is represented by way of a non-limitative example on the attached single drawing, which is a partially exploded perspective schematic view of the device according to the invention.

The object of the present invention is therefore to provide a device of robust and simple construction, and reliable and accurate in operation for the production of false selvedges on weaving looms.

The device according to the invention consists of two rods 1 and 2, preferably cylindrical, on which are slidably mounted two blocks, block 3, called the first block, and block 4, called the second block. Each of the rods 1 and 2 has at both its ends studs 5, 6, 7 and

8, which constitute on the one hand means of controlling the blocks 3, 4 and the linking plate 19, and on the other, abutments intended to limit the separation of these two blocks when under the influence of the wire spring 9 which, in the example shown, is wound into the shape of a hunting horn and connected by its ends to each of the blocks 3 and 4.

The abutments 5 to 8 comprise some slots 10 intended to allow the device to be fixed onto the blades 10 of the harness of a weaving loom, for example.

On the second block 4 is mounted pivotally by means of a spindle 11, a support part 12 for several thread guide units. In the example shown, these thread guides 13₁, 13₂, 13₃, 13₄, are four in number but not limited to this, and are constituted by needles with eyelets 16, at their free ends through which the fastening threads intended to constitute the false selvedge are threaded.

Likewise the first support block 3 receives a support part 14, but this part 14 can move slightly about the spindle 21 with respect to the block 3. This part 14 supports in the non-limitative example shown, four thread guides 15₁, 15₂, 15₃, 15₄ which also are provided with eyelets 17 at their ends for the passage of other fastening threads.

In the example shown, the second block 4 is made in the form of a frame on the edges of which slide the rods 1 and 2. This frame comprises at its lower end a lateral extension 18 provided with orifices through which the thread guide needles 15₁, 15₂, 15₃, and 15₄ can slide, the length of these needles being such that when the abutments 5, 6, 7 and 8 rest against the blocks 3 and 4, these needles project slightly through the orifices of this lateral projection. It is therefore seen that on account of this construction the needles 15₁ and 15₄ are guided to positioned correctly and that, in addition, if any vibration occurs while the needles 15₁ to 15₄ are in their high position, these vibrations are automatically eliminated as soon as these needles reach their low position. The construction also has the effect of preventing said needles entering into resonance.

The first block 3 which supports, in the oscillating position, the needles 15₁ to 15₄, also receives pivotally a linking part 19. In this construction, the part 14 is fixed to the block 3 by means of the screw spindle 21, the screws 20 and 22 being used to fix the needles, while the linking part 19 is mounted pivotally on the screw 21.

The linking part 19 is constituted by a plate, preferably made of metal, having two branches 19₁ and 19₂ which are joined at their free ends by a cross-piece 23 provided with orifices in which can slide the guide needles 13₁ to 13₄ mounted pivotally on the block 4 by means of the support 12.

Likewise, the length of the branches 19₁ and 19₂ of the linking plate 19 is such that when the abutments 5, 6, 7 and 8 are all resting against the blocks 3 and 4, the cross-piece 23 is located near the eyelets 16 of the ends of the needles 13₁ to 13₄. In consequence, as with the needles 15₁ to 15₄, the needles 13₁ to 13₄ are protected against any vibration and resonance phenomena that might occur.

It will be noted moreover that the branches 19₁ and 19₂ of the linking part 19 pass through the slots, respectively 24 and 25, formed at the base of the lateral extension 18, this arrangement avoiding vibrations of the linking plate while simultaneously eliminating the possibility of the needles 13₁ to 13₄ vibrating.

It will be noted in addition that, according to the invention, one of the needles, which in the examples is represented as needle 13₄ is of a greater length than the adjacent needles 13₁, 13₂ and 13₃. This arrangement has the result of making sure that the needles 13₁ to 13₄ do not strike the needles 15₁ to 15₄ head-on, when they cross one another because, before all the needles meet, the needle 13₄ has already been in contact with the end of the needle 15₄ and had forced all the needles 13₁ to 13₄ to pivot by means of the cross-piece 23.

The device operates as follows:

When the weaving loom is operating, the harness is driven in the opposite direction, so that the warp threads which pass through the heddle mail form the shed. As a result, the rods 1 and 2, each of which are connected to a harness by the slots 10 of the abutments 5, 6, 7 and 8 are driven simultaneously in the opposite direction, the abutments 5, 8, on one hand, and 7, 6 on the other, being, for each displacement, alternatively in contact with the blocks 4 and 3.

In fact, the abutments 6 and 8 do not rest directly on the first block 3, but instead, rest on the lower edge of the linking part 19 so that the alternative resting of the abutments 6 and 8 on each of the sides of the linking part 19, pivoting at 21, causes the linking part to tip in one direction or the other. Consequently, when the abutment 6 combines its action with the abutment 7, to bring closer to one another the needles 13₁ to 13₄ and 15₁ to 15₄, the abutment 6 makes the linking plate 19 pivot (to the right in the figure) and thus all the needles 13₁ to 13₄. Similarly, during the next displacement, it will be the abutments 5 and 8 which will control the movement of the needles approaching one another, the abutment 8 acting on the edge of the linking plate 19 so that the latter and the needles 13₁ to 13₄ pivot toward the left on the attached figure.

This pivoting movement of the needles 13₁ to 13₄ toward the right or toward the left with respect to the needles 15₁ to 15₄ occurs when the needles are approaching one another in a manner such that their ends cannot come into contact. However, if there were a tendency for this to occur, in spite of the particular construction of the device according to the invention, the needle 13₄ which is longer than its neighbours, would bear on the end of the needle 15₄ in order to force all the needles 13₁ to 13₄ to shift away from the needles 15₁ to 15₄. All risk of damage is therefore eliminated by the device according to the invention, in spite of the fact that the needles 13₁ to 13₄ are located respectively in the axis of the needles 15₁ to 15₄, when the device is in the rest position (position shown in the attached drawing).

What I claim is:

1. A device for producing a false selvedge on a fabric, comprising two rods together slidably receiving a first

block and a second block, each block supporting thread guides, said rods being provided at their ends with abutments for said blocks, spring means located between said blocks tending constantly to separate one block from the other, means for displacing the thread guides laterally during oscillation of the blocks with respect to one another, said device being characterized by the thread guides of the second block being mounted pivotally on said second block, a linking member being mounted pivotally on said first block, and said linking member having orifice means for slidably receiving during oscillation the thread guides of said second block.

15 2. A device according to claim 1, in which the thread guides of the first block are fixedly mounted on said first block and the second block has orifice means for slidably receiving said thread guides of the first block.

20 3. A device according to claim 2 in which the second block is of such a length that when the first and second blocks are resting against all said abutments, the orifice means of said second block are located close to the free ends of the thread guides of the first block.

25 4. A device according to claim 1 in which the linking member is of such a length that when the first and second blocks are resting against all said abutments the orifice means of said linking member are located close to the free ends of the thread guides of the second block.

30 5. A device according to claim 4 in which the linking member comprises a plate provided with two branches joined at their free ends by a part containing said orifice means for slidably receiving the thread guides of the second block.

35 6. A device according to claim 5 in which the second block is provided with slot means for slidably receiving the branches of said linking member.

40 7. A device according to claim 1 in which the linking member has a portion protruding slightly from said first block adjacent said abutments, whereby said linking member is pivoted back and forth by alternate contact of said abutments with said protruding portion of said linking member.

45 8. A device according to claim 1 in which the thread guides comprise needles provided at their free ends with thread guide eyelets.

9. A device according to claim 8 in which one of said needles is of a greater length than the others.

10. A device according to claim 9 in which the longest needle comprises one of the thread guides mounted pivotally on said second block.

50 11. A device according to claim 8 in which at the rest position the needles of the first block are mounted on the same axes respectively as the needles of the second block.
